UNITED STATES PATENT OFFICE.

ALFRED LEVY, OF PARIS, FRANCE, ASSIGNEE TO ALEXANDRE WALDBERG, OF PARIS,
FRANCE.

ELECTROLYTIC SOLUTION FOR CLEANING METALLIC ARTICLES.

1,061,089.

Specification of Letters Patent.

Patented May 6, 1913.

No Drawing.

Application filed December 4, 1912. Serial No. 734,895.

To all whom it may concern:

Be it known that I, ALFRED LEVY, of 65 Rue de Ranelagh, Paris, France, engineer, a citizen of the Republic of France, residing at Paris, France, have invented certain new and useful Improvements in Electrolytic Solutions for Cleaning Metallic Articles, of which the following is a full, clear, and exact description.

10 Electrolytic cleaning solutions as hitherto proposed present two grave difficulties which have prevented their general use in the electroplating industry. The first difficulty is that when the operator does not require to use graphite, which is very expensive, or agglomerated carbon which disintegrates very rapidly, he generally uses an iron anode which has been considered to be insoluble in such electrolyte; this insolubility however is 15 not real, as the iron anode is finally attacked under the action of the current, and the electrolyte is polluted and imperfect iron deposits are produced with the result that the preparation of the articles is interfered 20 with. The second difficulty is, that it is impossible to use such an electrolyte for cleaning soft metals or soldered metals, because, the electrolyte in spite of all precautions, attacks the white metals and the articles which 25 are to be cleaned show the presence of a white film which becomes more and more disturbing in subsequent operations, when the quantity of the dissolved white metal is increased. Besides, the presence of white 30 metal in the electrolyte causes the anode to be more quickly attacked with the result that the electrolyte has to be thrown away and replaced by a new one which has again as quickly to be replaced in its turn.

35 40 The present invention has for its object to radically remedy the two above mentioned difficulties.

For the purpose of meeting the first difficulty I use in the electrolytic cleaning electrolyte instead of alkaline cyanid, prussiate of potassium (ferro-cyanid or ferri-cyanid) which permits iron, steel, nickel or the like or any alloy of these or similar metals to be used as an anode. It would be even possible 45 to use as anodes a metal which would be attacked by the electrolyte under the influence of the current or not, if the products of such attacks were or would become insoluble in such electrolyte, but I do not recommend the 50 use of a metal which would be so attacked.

This electrolyte can be used without inconvenience for the purpose of all metals, except however of soldered metals or white metals.

To meet the second difficulty which presents itself when cleaning soldered or white metals, the above mentioned modification in the electrolyte would not be sufficient. But I obtain the desired result by adding to the electrolyte above described, a certain quantity of chalk; the simultaneous presence of a prussiate and of chalk (excluding any alkaline cyanid) will produce the desired result. As a matter of fact the prussiate which does not itself dissolve the soldered metal, nevertheless, does not prevent the dissolving of this solder by the alkaline body, which is the base of the electrolyte; and the passage of the current in such an electrolyte would lead to a white deposit. But the presence of chalk causes the precipitation of the white metal in the form of insoluble bodies, in proportion as it dissolves in the alkaline body it evidently would not be the same in the presence of an alkaline cyanid, which would dissolve the white metal in order to form a double cyanid, from which the chalk could not precipitate the white metal. The simultaneous employment of a prussiate and chalk (to the exclusion of any alkaline cyanid) is therefore indispensable in order 55 to obtain the desired result. With such an electrolytic cleaning bath, it will be necessary to stir the electrolyte from time to time so as to get the chalk into suspension again, and permit it to accomplish its work during 60 the course of the operation. When it is a question of cleaning articles made of a metal which can be employed as the anode in such a bath, such as iron, for example, one could, of course, use these articles successively as 65 anodes and cathodes, by reversing the direction of the current; and this would permit of the work being accomplished more rapidly. One might even if one is using certain definite anodes, as stated above, usefully 70 have recourse in certain cases to reversing the current. It is superfluous to state that with an electrolyte thus modified, one can employ anodes of graphite or of carbon, if one does not fear the objections attached to 75 their use, and referred to above.

The quantity of chalk to be employed may be very variable and, in case of need, a fresh quantity may be added to the bath after it has already been in operation. By way of 80

example I may state that a weight of chalk equal to one-tenth of the weight of the alkaline body which is the base of the electrolyte will be sufficient, but I do not bind myself to these proportions.

The following is the formula of a bath which gives excellent results:

Water----- 100 liters
Ferro-cyanid of potassium----- 1 kilogram
10 Caustic potash----- 10 kilograms
Chalk----- 1 kilogram

In the same way I do not bind myself to the exact proportions which may be modified 15 according to the circumstances.

The ferro cyanid of potassium in the above formula may be replaced by ferri cyanid of potassium and it is to be understood that the expression "prussiate of 20 potash" used in the appended claims is in-

tended to mean either the ferro or ferri cyanid of potassium.

I claim:—

1. An electrolytic solution for cleaning metallic articles, comprising a prussiate of 25 potash.

2. An electrolytic solution for cleaning metallic articles, comprising a prussiate of 30 potash, with the addition of chalk, as and for the purpose set forth.

3. An electrolytic solution for cleaning metallic articles, comprising a prussiate of 35 potash, caustic soda and chalk, as and for the purpose set forth.

In witness whereof I subscribe my signature in the presence of two witnesses.

ALFRED LEVY.

Witnesses:
